NEWTON D. HOLBROOK, OF THOMASTON, CONNECTICUT.

OPERATING MECHANISM FOR TIMEPIECES.

Application filed September 2, 1926. Serial No. 133,126.

This invention relates to mechanism which is designed for driving the time train of watch and clock movements in which the source of power is electrical, and while it is serviceable for electric clocks generally it is particularly adapted for time pieces used on automobiles. Automobile time pieces are subject to intensive vibration and unless the power is maintained uniform the 10 regularity of beat and accuracy of time-keeping is seriously affected, there is liability of over-banking with the result that they fail to run correctly if they do not stop.

time the magnet pull is utilized to keep the circuit closed until the driving spring is substantially tensioned. Means are provided to definitely limit the movement of the main 60 magnet armature and the make and break contact, and to prevent undue arcing of the contacts when the circuit is opened. The driving mechanism is connected with the time train driving arbor by positive means 65 but which is capable of slight expansion so as to keep the connection close at the instant that the main spring is tensioned, and thus contribute in maintaining the even driving pressure on the time train.

The object of this invention is to provide 15 a simple and reliable mechanism which is actuated for tensioning the main driving spring by periodical electric impulses, the intervals of which are controlled by the running of the time train, the driving mechanism being so composed and the connection so made that, although the source of power is periodic, the driving force is maintained uniform, even during the moments in which the electric impulses act for tensioning the main spring, whereby the time train will be driven by substantially steady pressure and the liability to inaccurate timing, over-banking and stopping will be eliminated.

This end is attained by providing an electromagnet, which may be composed of one, two or three windings, with two armatures, a main driving armature and a supplemental circuit controlling armature, both of 30 which are subject to the influence of the magnet. The driving armature under the pull of the magnet tensions the time train driving spring, which spring as the time train runs retracts the driving armature. The supplemental armature is flexible and carries a contact which is caused to close the circuit through the magnet when the main armature is retracted to the desired degree, and is caused to open the circuit 35 when the main armature is attracted substantially its full distance, the supplemental armature being actuated to an extent by the movements of the main armature but with a lost motion connection, whereby the circuit contacts are not instantly disengaged when the main armature is attracted but are held closed for a short interval by the magnetic pull upon the supplemental armature. With this arrangement the pull of the magnet is 40 employed to tension the time train driving spring and open the circuit, but at the same

In the accompanying drawings Fig. 1 is a view looking from the back of a driving mechanism having three magnet windings, which embodies the invention, the parts being in the position occupied when the 75 electric circuit is open. Fig. 2 is a view looking from the front of this form of the driving mechanism. Fig. 3 is a section taken on the plane 3-3 on Fig. 1, of the driving mechanism showing its connection with the 80 time train driving arbor. Fig. 4 is a section on the plane indicated by the dotted line 4-4 on Fig. 2. Fig. 5 is a view of the means that is attached to the driving arbor of the time train for the connection of the 85 driving mechanism therewith, the parts being shown in driving position. Fig. 6 is a similar view with the parts in the positions assumed at the instant the driving spring is tensioned. Fig. 7 is a plan view of a modified construction. Fig. 8 is an end view of the modified form, this modified arrangement having only one magnet winding.

In the first form illustrated the main driving magnet has two series connected 90 windings 1 on cores 2 fastened to the back of the plate 3. The armature 4 of this magnet is mounted so as to oscillate transversely toward and from the magnet cores, the rotatory spindle 5 to which it is fastened being 100 supported by a sleeve 6 that projects from the back of the plate. Fastened to the main driving armature spindle, on the front of the plate is a rocker 7. Pivoted to the section 8 of this rocker is a pawl 9. One end 105 of the main driving spring 10 is connected between this pawl and a pin 11 fastened to the plate, in such manner as to pull the rocker and oscillate the armature from the magnet cores and at the same time cause the 110 pawl to engage the teeth of a driving ratchet wheel 12. A pawl 13 is held in engagement

with the ratchet wheel teeth by a spring 14 so as to prevent this wheel from turning backward when the driving pawl is retracted. The ratchet wheel has two forwardly extending pins 15 that are designed to, when the wheel is rotated by the push of the pawl, engage the fingers 16 which are attached to a disk 17 fastened to the driving arbor 18 of the time train. When the driving pressure is exerted on the time train these fingers close together and provide a positive driving connection, as illustrated in Fig. 5, but at the instant that the driving spring is tensioned and the driving pressure tends to relax the resilience of these fingers causes them to spring out, as shown in Fig. 6 and thus keep them in close engagement with the pins on the ratchet wheel at all times. The end 19 of the rocker 7 is bent backward through a slot 20 in the plate and terminates in a fork 21 on the other side of the plate. By means of these elements when the magnets are energized by closing the circuit the driving armature is oscillated toward the cores so as to turn the rocker and tension the driving spring and retract the pawl over the teeth of the ratchet wheel. When the circuit through the magnets is opened the spring retracts the driving armature and through the pawl turns the ratchet wheel so as to drive the time train. This action is repeated as frequently as the magnets are energized and deenergized.

One terminal of the main magnet windings is connected with a binding screw 22 to which one lead from the source of electrical energy is attached. The other terminal of the main magnet windings is connected with one end of the winding of a supplemental magnet 23. The other end of the supplemental magnet winding is connected with a contact 24. This supplemental or switching magnet is smaller and less powerful than the main driving magnet. The armature 25 of the supplemental magnet is mounted on a spring finger 26 of conducting material which at its free end has a contact 27 adapted to engage with the contact 24, and at the other end the finger is fastened to the plate by a stud 28. This finger is in electrical connection with a binding screw 29 for the attachment of one of the leads from the source of electrical energy. The spring finger carrying the armature and contact passes between and is adapted to be engaged by the prongs of the fork 21 on the end of the section 19 of the rocker that is fastened to the main driving armature spindle. The space between the fork prongs is wider than the thickness of the finger so that there will be a lost motion engagement between these parts, that is, so that the fork will move some distance before it engages and moves the finger.

A resistance 30 may be connected in the

circuit around the main driving magnets, that is, from one side of the main magnet windings to the other side of these magnet windings, for the purpose of shunting these windings and eliminating arcing when the contacts adjacent to the supplemental magnet are disengaged and the circuit is opened.

When this arrangement of the mechanism is connected in series with a source of electrical energy and the contacts at the end of the supplemental magnet and on its spring armature are engaged, current flows through both the main and supplemental magnets and the pull of the main magnets oscillates the main driving arbor and causes it to tension the main driving spring. As this occurs the fork releases the spring armature of the supplemental magnet which then tends to spring out and open the circuit, but owing to the magnetism of the supplemental magnet this contact is retained in engagement for an instant or until the lost motion of the fork is taken up and then the fork engages the spring armature and causes it to open the circuit. With the circuit open and the driving spring under tension the time train runs until the pawl under the pull of the driving spring has reached the desired limit of its movement. During this movement the fork is moving back and is carrying the spring armature contact toward the fixed contact. When the contacts again engage and the circuit is remade the driving armature is again oscillated and the action of the parts is repeated. As stated, owing to the lost motion between the fork and the spring armature finger and the magnetic pull of the supplemental magnet, the engagement of the contacts is not instantly broken when the current is sufficiently reduced in the main magnets to permit the pull of the main driving magnet spring to retract the main driving armature. There is a slight interval of time between the action of the main driving armature and the action of the spring armature and this permits the driving spring to be fully tensioned before the circuit is completely broken. The pull of the supplemental magnet insures positive engagement of the contacts, and whatever tendency there is to back lash or resistance from the time train is eliminated by the spring fingers which connect the driven ratchet wheel with the time train driving arbor. The fork is limited in its movement by the ends of the slot through which it passes and therefore the amount of oscillation of the main driving magnet is always the same, which results in a uniform tension being given to the driving spring and an exact amount of movement given to the armature finger, and thus insures an accurate uniform maintained force being imparted from the driving mechanism to the time train.

In the above described arrangement there are three magnet windings. In the modified form illustrated in Figs. 7 and 8 substantially the same is accomplished with but a 5 single magnet winding 31 on a core 32. The main driving armature 33 of this arrangement is pivotally mounted on a stud 34 at the back of the plate 35. This armature has an angularly extending arm 36 that has a 10 lug 37 which extends through a slot in the plate and on the front is connected with the driving spring 38 that is tensioned when the armature is attracted toward the core of the magnet. The free end of this arm is 15 bent outward and has a slot 39.

The supplemental or circuit controlling armature 40 is in the shape of a spring finger which is fastened to the arm projecting from the main armature, and extends freely 20 through the slot in the bent end of the arm. This supplemental armature is adapted to be attracted by the magnetic pull of the extension 41 from the end of the core 32. The supplemental armature carries a contact 42 25 which is designed to engage a fixed contact 43 on the finger 44 which is fastened to the end of the magnet and to which one end of the magnet winding is connected.

The action of this modified arrangement 30 is substantially the same as that of the arrangement first described. As the time train runs under the pull of the driving spring the main armature is retracted until the contact on the supplemental armature attached to the main armature engages the 35 fixed contact. This closes the circuit and the main armature is then attracted and the driving spring tensioned. The movement of the driving armature when attracted 40 is in such a direction as to tend to disengage the contacts and open the circuit. However, owing to the lost motion connection 45 between the walls of the slot in the end of the arm extending from the main armature, and the spring finger supplemental armature, the circuit is not instantly opened for the magnet holds the supplemental armature with the circuit contacts engaged until the lost motion is taken up and then the further 50 movement of the main armature causes the contacts to separate and the circuit to become broken. This, however, does not take place until the main driving spring is practically fully tensioned.

55 In both forms illustrated and described, whether the operating magnet is divided so as to have three windings or it has only one winding, when the circuit is closed the same magnetic impulse which causes the main armature to tension the driving spring and open the circuit is exerted on the supplemental armature to retain the circuit closed until the lost motion between the two is taken up and the driving spring is given a substantial driving tension.

The invention claimed is:

1. A time train driving mechanism comprising a main driving magnet, a supplemental switching magnet in series therewith, a driving armature for the main magnet, a 70 switching armature for the supplemental magnet adapted to open and close the circuit through the magnets, a time train driving wheel, a pawl engaging said wheel, a spring arranged to cause the pawl to drive 75 said wheel, and means actuated by the movements of the driving armature for tensioning the driving spring and retracting the pawl, said means also adapted to engage and move said switching armature of the supplemental magnet.

2. A time train driving mechanism comprising a main driving magnet, a supplemental switching magnet in series therewith, a driving armature for the main magnet, a 80 switching armature for the supplemental magnet adapted to open and close the circuit through the magnets, a time train driving wheel, a pawl engaging said wheel, a spring arranged to cause the pawl to drive 85 said wheel, and means actuated by the movements of the driving armature for tensioning the driving spring and retracting the pawl, said means including a fork having a lost motion engagement with said switching 90 armature of the supplemental magnet.

3. A time train driving mechanism comprising a main driving magnet, a supplemental switching magnet in series therewith, an oscillatory driving armature for the main 100 magnet, a switching armature for the supplemental magnet adapted to open and close the circuit through the magnets, a time train driving wheel, a pawl engaging said wheel, a spring arranged to cause the pawl 105 to drive said wheel, and means oscillated with the driving armature for tensioning the driving spring and retracting the pawl, said means also adapted to engage and move said switching armature of the supplemental 110 magnet.

4. A time train driving mechanism comprising a main driving magnet, a supplemental switching magnet in series therewith, a driving armature for the main magnet, a 115 conducting spring finger bearing an armature for the supplemental magnet and a contact adapted to open and close the circuit through the magnets, a time train driving wheel, a pawl engaging said wheel, a spring arranged to cause the pawl to drive 120 said wheel, and means actuated by the movements of the driving armature for tensioning the driving spring and retracting the pawl, said means also adapted to engage and move said spring finger.

5. A time train driving mechanism comprising a main driving magnet, a supplemental switching magnet in series therewith, an oscillatory driving armature for 125

- the main magnet, a rocker connected to and oscillating with said armature, a switching armature for the supplemental magnet adapted to open and close the circuit through the magnets, a time train driving wheel, a pawl carried by said rocker and engaging said wheel, and a spring connected to and tensioned to cause the pawl to drive said wheel.
10. 6. A time train driving mechanism comprising a main driving magnet, a supplemental switching magnet in series therewith, an oscillatory driving armature for the main magnet, a rocker connected to and oscillating with said armature, a switching armature for the supplemental magnet adapted to open and close the circuit through the magnets, a time train driving wheel, a pawl carried by said rocker and engaging said wheel, a spring connected to and tensioned to cause the pawl to drive said wheel, and a fork on said rocker adapted to engage and move the armature of the switching magnet, said fork extending through a slot in the supporting plate and engaging the walls thereof for limiting its movement and the movement of the driving armature.
15. 7. A time train driving mechanism comprising a main driving magnet, a supplemental switching magnet in series therewith, an oscillatory driving armature for the main magnet, a switching armature for the supplemental magnet, a time train driving wheel, pins extending from said wheel, spring fingers engaged by said pins and adapted to be connected with the driving arbor of a time train, a driving spring, a pawl between said wheel and spring, and a rocker actuated by the movements of the driving armature for tensioning the driving spring and retracting the pawl, said rocker also engaging and moving the switching armature.
20. 8. A time train driving mechanism comprising a main driving magnet, an oscillatory armature for said magnet, a driving spring, means actuated by the oscillations of said armature for tensioning the driving spring, a supplemental switching magnet in series with the main magnet, a switching armature for the supplemental magnet, and means actuated by the oscillations of the driving armature adapted to engage and cause the switching armature to open and close the circuit through the magnets.
25. 9. A time train driving mechanism comprising a main driving magnet, a supplemental switching magnet in series therewith, an oscillatory driving armature for the main magnet, a switching armature for the supplemental magnet, a time train driving wheel, pins extending from said wheel, spring fingers engaged by said pins and adapted to be connected with the driving arbor of a time train, a driving spring, a pawl between said wheel and spring, and a rocker actuated by the movements of the driving armature for tensioning the driving spring and retracting the pawl, said rocker also engaging and moving the switching armature.
30. 10. A time train driving mechanism comprising a main driving magnet, an oscillatory armature for said magnet, a driving spring, means actuated by the oscillations of said armature for tensioning the driving spring, a supplemental switching magnet in series with the main magnet, a switching armature for the supplemental magnet, and means actuated by the oscillations of the driving armature adapted to engage and cause the switching armature to open and close the circuit through the magnets.
35. 11. A time train driving mechanism comprising a main driving magnet, a supplemental switching magnet in series therewith, an oscillatory driving armature for the main magnet, a switching armature for the supplemental magnet, a time train driving wheel, pins extending from said wheel, spring fingers engaged by said pins and adapted to be connected with the driving arbor of a time train, a driving spring, a pawl between said wheel and spring, and a rocker actuated by the movements of the driving armature for tensioning the driving spring and retracting the pawl, said rocker also engaging and moving the switching armature.
40. 12. A time train driving mechanism comprising a main driving magnet, a supplemental switching magnet in series therewith, an oscillatory driving armature for the main magnet, a switching armature for the supplemental magnet, a time train driving wheel, pins extending from said wheel, spring fingers engaged by said pins and adapted to be connected with the driving arbor of a time train, a driving spring, a pawl between said wheel and spring, and a rocker actuated by the movements of the driving armature for tensioning the driving spring and retracting the pawl, said rocker also engaging and moving the switching armature.
